TYPEWRITING MACHINE

George F. Handley, Glendale, N. Y., assignor to
Royal Typewriter Company, Inc., New York,
N. Y., a corporation of New York

Application February 5, 1941, Serial No. 377,570

24 Claims. (Cl. 197—114)

This invention relates to typewriting machines, and more particularly to mechanism for feeding and positioning continuous webs comprising a plurality of connected form sheets.

In the typing of a plurality of similar invoices, checks, or similar forms, it is common practice to supply a continuous web or sheet comprising a plurality of serially connected individual forms which are fed successively to and then beyond the printing line as following forms move into printing position. The individual forms comprising the continuous web may all be the same, so that the beginning or first typed lines on all the forms will be equally spaced below the tops of the respective forms. The distance between the last line of typing on each form and the first line of typing on the next succeeding form may vary, depending upon the typing of different numbers of lines on different forms, but in any event it usually is the equivalent of a rather large number of the spaces between individual lines, i. e., "line spaces." In the interest of ease and rapidity of operation in the typing of such forms, it is desirable to provide mechanism including a member a single actuation of which, following the completion of typing on one of a series of connected forms and regardless of the number of lines typed on that form, will advance the web to position the next succeeding form for receiving its first line of typing in the same relative position, on the newly positioned form, as the first line of typing on the completed form. Such mechanism, broadly considered, has been proposed heretofore, and one of the objects of the present invention is to provide improved and efficient mechanism for feeding a web in the manner explained above.

Another object is to provide such mechanism with means for easily varying or selectively determining its feeding capacity or limits so as to make it readily adjustable to two conditions. For example, the first such condition may be for feeding the web just the correct amount to position the leading form to receive the first line of typing, and the second condition may be for thereafter feeding the web a different amount following the completion of typing on each of the forms to position the next succeeding form to receive its first line of typing.

Other objects will become apparent from a reading of the following detailed description, the appended claims, and the accompanying drawings, in which:

Figure 1 is a fragmentary plan view showing only some of the conventional parts of a type-

writer carriage, with mechanism embodying the invention applied thereto;

Figure 2 is a fragmentary side elevation looking in the direction of the arrow 2 in Figure 1 with a sheet-feeding cylinder or platen shaft being shown in section and the parts of the web-feeding mechanism being shown in their normal or inactive positions;

Figure 3 is a fragmentary vertical cross section taken on the line 3—3 of Figure 2 drawn on an enlarged scale, and showing parts in positions different from those they occupy in Figure 2;

Figure 4 is a transverse sectional view taken substantially on the irregular lines 4—4 of Figure 1 and showing the parts in the positions occupied at the end of the operation which positions the first of a series of forms in a web or work sheet for being typed upon;

Figure 5 is a detailed transverse section taken on the irregular lines 5—5 of Figure 4 and drawn on an enlarged scale;

Figure 6 is a detailed vertical sectional view taken on the line 6—6 of Figure 4 and drawn on an enlarged scale;

Figure 7 is a view similar to Figure 2 but showing the parts in the positions occupied at the end of an operation for advancing a work sheet or web from its position following the last line of typing on one form to a position in which the next or adjacent form is positioned for receiving a first line of typing;

Figure 8 is a view similar to Figure 2 but showing the parts in the same positions as in Figure 4;

Figure 9 is a fragmentary transverse sectional view of a web-feeding cylinder or platen, pressure rolls, and paper pan;

Figure 10 is a fragmentary transverse sectional view showing the cylinder, paper pan, pressure rolls, and an overhead bail;

Figure 11 is a detailed view partly in elevation and partly in section showing a known line-spacing detent mechanism;

Figure 12 is a fragmentary longitudinal sectional view taken on the line 12—12 of Figure 1 and drawn on an enlarged scale;

Figure 13 is a longitudinal sectional view taken on the line 13—13 of Figure 2;

Figure 14 is a deployed perspective view of an oscillating bar frame and cooperating parts; and

Figure 15 is a diagrammatic development showing a work sheet or web including a series of check forms and indicating the relative lengths of spacing corresponding to sheet-feeding and line-spacing movements.

The drawings show only such parts of conven-

tional typewriter construction as are necessary for an understanding of the manner in which paper-feeding mechanism embodying the invention may be applied to typewriters.

A part of a typewriter frame is indicated at A and is provided with the usual frame rail 1 which supports the rail 2 of a carriage B by means of ball bearings 3. The carriage includes the usual end plates 4—4 (for the left-hand end plate, see Figure 11). A bushing 5 carried by the right-hand end plate 4 journals the right-hand end of a shaft 6 to which a sheet-feeding platen or cylinder 7 is fixed. Extension posts 8 and a bracket 9 projecting outwardly from the right-hand end plate 4 serve to mount a supplemental end plate 10 which, as explained hereinafter, mounts the feeding mechanism embodying the invention. The shaft 6 is extended through and beyond the supplemental end plate 10 and its projecting end is provided with the usual platen-rotating finger knob 11. As shown in Figure 11, the cylinder shaft 6 is equipped with a line-spacing ratchet wheel 12 adapted to be yieldably held at line-spacing intervals by means of a pawl 13 pivoted as at 14 on the left-hand carriage end plate 4. A spring 15 connected to the pawl 13 and anchored on the carriage end plate 4 at a point not shown urges the pawl yieldably in a clockwise direction to effect yielding contact of the pawl roller 16 with the teeth of the ratchet wheel 12. This line-spacing ratchet and detent mechanism is of known form, being standard equipment in the Royal typewriter. As is well known, it serves to yieldably determine the successive definite positions in which the platen or cylinder 7 is yieldably held for determining predetermined line spaces. The typewriter may also be equipped with a known or suitable form of combined carriage return and line-spacing lever D adapted to drive a pawl engageable with the teeth of the ratchet wheel 12 for effecting line-spacing as an alternative to turning the platen or cylinder by means of the finger knob 11.

As shown in Figures 9 and 10, a paper pan 17 projecting downwardly from the rear of the platen and then under the platen toward the front of the latter is formed with openings 18 and 19 for accommodating rear and front pressure rolls 20 and 21, respectively, adapted to cooperate with the platen 7 for feeding the work sheet C from the rear of the platen, under it, and then up in front of the platen so as to be disposed at the printing line to be impacted by the type bars, one of which is shown in printing position at 22. When the work sheet or web C is first fed into the machine, the leading edge thereof is extended upwardly behind rollers 23 carried by an overhead bail 24, the rollers 23 and bail 24 then being in the positions shown in full lines in Figure 10. Then the bail 24 and rollers 23 are moved rearwardly to the positions indicated in dotted lines in Figure 10 for holding the sheet snugly about the platen 7.

With the exception of the supplemental end plate 10 and its mounting on the carriage, the parts thus far described are of known form and relative arrangement, and do not constitute the present invention. The invention comprises other parts to be described and combinations of such other parts with each other and with the parts referred to above.

Before describing in detail the illustrative embodiment of the invention, and in order to facilitate an understanding of the detailed descrip-

tion which is to follow, reference first is made to the diagrammatic showing in Figure 15, which indicates the desired steps of feeding which the mechanism is intended to accomplish. The work sheet or web C comprises a plurality of serially arranged check forms c¹, c², c³, c⁴, and c⁵ connected by lines of perforations at regular intervals. It is desired to type the first line L¹, L², L³, L⁴, and L⁵ of each form at the same distance below the top edge of the form and to type an additional line or lines under the first line on each form, the number of additional lines on the several forms being different in some cases. Thus, the form c¹ may have four typed lines altogether; the form c² three typed lines; the form c³ five typed lines; the form c⁴ six typed lines; and the form c⁵ three typed lines. It is desired to advance the web with certainty and rapidity to exactly the right position for receiving the first line L¹ of the form c¹, and then with equal ease and rapidity to position the successive forms for receiving their initial typed lines regardless of how many lines have been typed on the preceding form.

The distance S which the web must travel from the time its leading edge first engages the platen and rear pressure roller 20 as shown in Figure 9 until it is in position for receiving first line L¹ on the leading form c¹ will be a fixed amount, and, for the purposes of illustration, will be assumed to correspond to twenty-three letter-spacing increments. Similarly, the distance s between the first typed line of each form and the first typed line of each succeeding form will be fixed and will be assumed to be equivalent to twenty letter-space increments. The rotation of the platen 7 for line-spacing the web for the second and other additional lines on each sheet is effected by means of the usual line-spacing mechanism, such as the finger knob 11 or the combined carriage return and line-spacing mechanism. The feeding of the web for moving it from the position shown in Figure 9 to the position for receiving the typed line L¹ on the form c¹ is accomplished by a single actuation of an operating member 25 having a handle 26. Advancing of the web from the position occupied during the typing of the last line on any form to the position for receiving the first line on the next form also is accomplished by a single actuation of the member 25, and, inasmuch as this continuous feeding movement will differ from the movement which first positioned the form c¹ for the reception of the line L¹, a selector device 27 having a finger piece 28 is provided for selectively determining the limit of movement of the manually operable member 25. As herein-after is explained in more detail, the finger piece 28 of the selector device 27 is depressed, and the member 25 pushed rearwardly to the limit of its travel to position the form c¹ for the reception of the line L¹, whereas, for advancing the web from the position occupied when typing of the last line on the form c¹ has been completed to a new position for reception of the line L² on the form c², the finger piece 28 of the selector device 27 is released, and the member 25 then pushed to a different limit of its rearward movement.

In the form shown, the manually operable member 25 comprises a rack which is reciprocable fore and aft in a bar frame 29 having a fixed stud 30 pivoted in an ear 31 on the supplemental end plate 10 whereby the bar may be oscillated up and down about the stud 30 in a plane transverse to the axis of the shaft 6. The rear end

of the frame 29 is formed with an integral plate portion 32 which supports a separate plate 33 through the medium of connecting pins having reduced ends 34 fixed to the plate 33, large spacing portions 35 intervening between the plate 33 and the plate portion 32, and threaded ends 36 extending through the plate portion 32 for receiving securing nuts 37. The plate portion 32 and plate 33 carried thereby hold the rack 25 against lateral movement, and rollers 38 journaled on the enlarged pin portions 35 anti-frictionally maintain the rack 25 against vertical movement, but permit the rack to slide freely back and forth parallel to the frame 29. The front end of the frame 29 is formed integrally with upper and lower guide portions 39 and 40, respectively, which prevent the forward end of the rack from moving vertically with respect to the frame 29. An angle piece 41 secured to the frame by screws 42 and having a vertically extending leg 43 projecting alongside the rack 25 constrains the latter to slide parallel to and close against the frame 29. The arrangement is such that the rack 25 is free to slide fore and aft in the frame 29, and is oscillatable in a vertical plane with the frame 29 about the pivot stud 30. The vertical oscillating movement of the frame and rack is limited by engagement of a screw 44 carried by a frame ear 45 with the opposite ends of a slot 46 in the supplemental end plate 10. The head of the screw 44 also prevents lateral movement of the forward end of the frame 29 and rack 25.

The rack 25 constantly is urged forwardly by means comprising a spring barrel 47 supported on the supplemental end plate as at 48, and a draw cord 49 wound upon the spring barrel 47 and extending in contact with a guide pulley 50 for connection to a post 51 on a clamp 52 secured to the rear end of the rack. A finger bracket 53 secured to the rack by means of screws 54 is adapted to engage the guide portion 39 on the frame 29 for limiting the forward movement of the rack under the urge of the spring barrel 47 and draw cord 49.

Normally, the frame 29 and rack are in their lower positions as shown in Figures 2, 12, and 13, with the rack 25 meshing with a gear 55 secured by a set screw 55a to the platen shaft 6. The frame and rack are releasably held in these normal positions by engagement of a pin 56 on the frame 29, with the upper wall of a slot part 57 of a holding member 58 pivoted as at 59 on the supplemental end plate 10, the slot 57 preferably being concentric to the pivot 59. The holding member 58 is formed with an enlarged or clearance opening 57a communicating with the slot 57, the arrangement being such that when the holding member 58 is rocked clockwise from the position shown in Figure 2 the pin 56 may rise in the clearance opening 57a to permit the frame 29 and rack 25 to swing upwardly to disengage the rack from the gear 55 for a purpose to be described later. The top wall of the enlarged clearance opening 57a will limit upward movement of the pin 56, the frame 29, and the rack 25. The holding member 58 is releasably held in its normal (Figure 2) position by means of a spring 60 interposed between a lower extension 61 of the holding member and a lower extension 62 of a lifting finger 63 pivoted on the supplemental end plate as at 64. The spring 60 is normally held under tension by means of another spring 65 interposed between the lifting finger 63 and a lower extension 66 of a

latch 67 pivoted on the supplemental end plate 10 as at 68, the latch 67 normally being held in the position shown in Figure 2 by engagement with a pin 69 fixed to the oscillatory frame 29.

5 A U-shaped block 70 is secured to the rack 25 adjacent its outer end, and a screw 71 passing through the block 70 and rack pivotally supports the selector device 27. A spring 72 interposed between an ear 73 on the selector device and a post 73a on the rack 25 yieldably urges the selector device 27 to its normal position as shown in Figures 1, 2, and 7, wherein the rearmost end of the selector device 27 is projected rearwardly beyond the rear end of the block 70. The finger piece 28 provides for the lifting of the selector device 27 against the urge of the spring 72 so as to position the selector device as shown in Figures 4, 5, and 8. When the selector device is in its normal position and the rack is pushed rearwardly, a pin 74 on the selector device is adapted to engage the holding member 58 for moving the latter to the position shown in Figure 7 to release the holding member and permit the rack to be moved upwardly and out of mesh with the gear 55. When the selector device is raised by depression of the finger piece 28 and the rack is moved rearwardly, a pin 75 on the U-shaped block 70 will engage the holding member 58 to move it rearwardly. The selector device 27 is formed with a groove 76, through which the pin 75 extends.

When the rack has moved to the limit of its rearward travel, and either the pin 74 or the pin 75 has moved the holding member 58 to the position shown in Figure 7, the rack is raised out of engagement with the gear 55. To prevent retrograde movement of the platen at this time, a safety lock dog 77 is pivoted as at 78 on the supplemental end plate 10, and has a nose 79 engageable with the teeth of the gear 55 as shown in Figure 4. Normally, the lock dog 77 is held in its inoperative position by means of a spring 80 interposed between an arm 81 on the dog and a post 82 on the supplemental end plate 10, movement of the dog under the urge of the spring 80 being limited by engagement of the dog with a stop pin 83 mounted on the supplemental end plate 10. The dog is urged into engagement with the teeth of the gear 55 by the rearmost end of either the selector device 27 or the U-shaped block 70, depending upon whether the selector device is in its lower or its raised position.

Operation

Before inserting a sheet C in the typewriter, the overhead bail 24 is moved forwardly to the position shown in Figure 10 so as to position the bail roll 23 slightly in advance of the platen 7. The leading edge of the sheet C is then positioned in contact with the platen 7 and the rear pressure roll 20, as shown in Figure 9. The rack 25 and associated parts at this time will be in the positions shown in Figures 1, 2, 12, and 13, with the rack engaging the gear 55. To move the web C so as to position the leading check form C¹ in position for typing of the first line L¹ requires a total movement corresponding to twenty-three letter-spacing increment movements of the platen 7, and requires a definite rearward travel of the rack 25. To permit the rack to travel rearwardly to the required extent, the finger piece 28 on the selector device 27 is depressed so as to raise the selector device to the position shown in Figures 4, 5, and 8. The rack 25 is then pushed rearwardly in the operating direction in one continu-

ous sweep or movement so as to rotate the gear 55 and platen 7 continuously. During operating movement of the rack, it is maintained in mesh with the gear 55 by the top wall of the slot 57 engaging the pin 56. When the pin 75 on the U-shaped block 70 attached to the rack engages the holding member 58, the latter will be swung clockwise from the position shown in Figure 2 to the released position shown in Figure 8 to free the pin 56 from the slot 57 and to position the clearance opening 57^a above the pin 56 on the frame 29. Rearward movement of the rack is finally arrested by engagement of a rack stop constituted by the rear end of the block 70 with a frame stop constituted by the front end of the frame 29, the stopping of the rack being effected when the sheet C has been fed a total distance corresponding exactly to twenty-three letter-spacing increments of the platen, and the check form c¹ will be positioned for receiving the first line of typing L¹. Just prior to engagement of the block 70 with the front end of the frame 29, the rear end of the block 70 will engage the safety lock dog 77 and move it to the position shown in Figure 4, wherein its nose 79 is engaged between two adjacent teeth of the wheel 55 so as to prevent any overthrow or retrograde movement of the platen when the rack is raised out of engagement with the gear 55, as explained hereinafter.

Clockwise rocking of the holding member 58 by the pressure of the pin 75 will have additionally tensioned the spring 60, so as to urge the lifting finger 63 clockwise with sufficient force effectively to promote lifting of the pin 56 as permitted by the enlarged clearance opening 57^a. The pin 56, in being lifted or urged upwardly by the lifting finger 63, rocks the frame 29 and rack 25 upwardly to the position shown in Figure 8 so as to disengage the rack from the gear 55. When the frame 29 is rocked upwardly, the pin 69 thereon moves to a level above the nose of the latch 67, whereupon the spring 65 rotates or rocks the holding latch 67 to move the nose under the pin 69 and hold the frame 29 and rack 25 in the elevated position as shown in Figure 8.

The operator then releases the rearward pressure on the rack 25, whereupon the spring barrel 47 and cord 49 will pull the rack from its Figure 8 position forwardly until a rack stop constituted by the finger bracket 53 engages a frame stop constituted by the rear end of the upper guide projection 39 on the frame 29, which determines the limit of return movement of the rack. During its entire return travel the rack is maintained out of mesh with the gear 55 by the engagement of the nose of the latch 67 with the pin 69. Just prior to engagement of the finger bracket 53 with the guide projection 39, the finger bracket will engage the upper end of the latch 67 and swing the latch counterclockwise so as to move the latch nose from under the pin 69. The counterclockwise rotation of the latch additionally tensions the spring 65 so as to rock the lifting finger 63 and thereby additionally tension the spring 60, thus urging the holding member 58 counterclockwise. The inclined wall 57^b of the enlarged opening 57^a between the top wall thereof and the slot 57 will be pressed against the pin 56 to urge the frame 29 and rack 25 to swing downwardly, assisted by gravity, to bring the rack again into mesh with the gear 55. Finally the spring 60 will restore the holding member to the position shown in Figure 2 with the pin 56 received in the

slot 57. The mechanism will then be in readiness for line-spacing operation or another sheet-feeding operation.

Such feeding operation having been effected, the sheet C will be in the position shown in full lines in Figure 10, with the leading edge thereof projecting up from the platen and behind the bail rollers 23. Before typing is begun, the bail 24 and roller 23 are moved rearwardly to the position shown in dotted lines in Figure 10, wherein the rollers 23 hold the sheet C snugly about the platen 7. It will be assumed for the moment that only one line is to be typed on each of the forms, and that the distance between this line on each pair of adjacent forms corresponds to twenty letter-space increments. To feed the sheet C exactly twenty letter-space increments after the typing of the line L¹ and so as to position the form c² for receiving the line of typing L², the rack 25 is pushed rearwardly, but this time with the selector device 27 remaining down on the rack 25, that is, in the position shown in Figure 2. The rearward movement of the rack this time will be stopped by engagement of a rack stop constituted by the rear end of the selector device 27 with the frame stop constituted by the front end of the frame 29. The rear end of the selector device is positioned to the rear of the rear end of the lock 70 a distance such that the rack will be arrested after the platen has been moved a distance corresponding to twenty letter-spacing increments instead of the twenty-three letter-spacing increments it was moved when the selector device 27 was raised and the rack was stopped by engagement of the block 70 with the frame 29. Just prior to engagement of the block 70 with the frame 29, the pin 75 on the block will have pushed the holding member 58 rearwardly to the position shown in Figure 8 so as to permit the lifting finger 63 to lift the pin 56, the frame 29, and the rack 25, after which the nose of the latch 67 will move under and support the pin 69, the frame 29, and the rack 25. The rack will then again be returned to its forward position by the spring barrel 47 and winding cord 49. The sheet then will have been fed to position the check form c² for receiving the line of typing L². Positioning of the succeeding forms for receiving their respective lines of typing L³, L⁴, L⁵ will be accomplished in a similar manner.

When it is desired to type more than one line on each card, it still is desirable, following the last line of typing on one form, to feed the sheet C to position the next form for the reception of its first line of typing through a single operation of the rack 25. Thus, after the first line L¹ has been typed on the form c¹, the platen and sheet C may be line-spaced for three successive lines by operation of the finger knob 11 or the conventional line-spacing lever D cooperable with the line-spacing ratchet wheel 12. During each line-spacing movement effected by the finger knob 11 or the line-spacing lever, the gear 55 will rotate and will drive the rack 25 rearwardly, and thus lessen the amount of rearward travel of the rack which subsequently can be effected by pushing the rack to drive the gear 55 and platen 7. The amount of movement of the platen 7 which can be effected by thereafter pushing the rack 25 rearwardly will be complementary to the number of line-spacing movements effected by the finger knob 11 or line-spacing lever, so that the total number of line-spacing movements including those effected by operation of the knob 11 or line-spacing lever, together with those effected by the

subsequent pushing of the rack, will be exactly equal to twenty line-spacing increments, and the first line L^2 of the form c^2 will be positioned at the printing point. It is apparent that the sum of the line-spacing increments effected by operation of the knob 11 or line-spacing lever and those effected by subsequent pushing of the rack will be constant regardless of how many lines are typed on each form.

When using the mechanism shown in the manner described, the selector device 27 is operated to condition the feeding mechanism selectively for positioning the first of a set of connected forms for receiving its first line of typing, or for positioning a succeeding form for receiving its first line of typing after the first form already has been typed. Ordinarily the distance between the first line of successive connected forms always will be the same, so that the selector device is not moved after a sheet or web of continuously connected forms has been inserted in the machine. However, it is evident that the selector device also could be used in the case of forms which, within the continuous web or sheet itself, vary as to the distance between initial lines of typing on adjacent forms.

The spring 15 urges the detent roller 16 against the ratchet wheel 12 with sufficient force to prevent the spring barrel 47 from effecting return movement of the rack 25 and reverse rotation of the platen in the event the operator discontinues exerting rearward pressure on the rack during an operating stroke.

The mechanism disclosed herein embodies the invention in the form now preferred, but it will be understood that various changes may be made in the construction and relative arrangement of the parts without departing from the invention as defined in the claims.

I claim:

1. In a typewriting or the like machine, the combination of a rotatable sheet-feeding cylinder, a cylinder-operating member mounted for movement in an operating direction to effect sheet-feeding cylinder rotation and in a return direction following such cylinder rotation; other means for rotating the cylinder to effect line-spacing movements thereof; means effective irrespective of preceding line-spacing accomplished by said other means for providing driving connection between the cylinder-operating member and the cylinder at all times except during the return movement of said member; and a device for determining selectively two different limits of movement of said cylinder-operating member in the operating direction.

2. In a typewriting or the like machine, the combination of a rotatable sheet-feeding cylinder, a cylinder-operating member mounted for movement in an operating direction to effect sheet-feeding cylinder rotation and in a return direction following such cylinder rotation; first stop means for limiting movement of said cylinder-operating member in said operating direction, said first stop means comprising a device for determining selectively two different lengths of movement of said cylinder-operating member in said operating direction; second stop means for limiting movement of said cylinder-operating member in said return direction; other means for rotating the cylinder to effect line-spacing movements thereof; and means effective independently of preceding line-spacing accomplished by said other means for providing driving connection between said cylinder-

operating member and said cylinder during the entire movement of said member from its limit position determined by said second stop means to its limit position determined by said first stop means, said drive connection means being ineffective during movement of said member from its limit position determined by said first stop means to its limit position determined by said second stop means.

3. In a typewriting or the like machine, the combination of a rotatable sheet-feeding cylinder, a cylinder-operating member mounted for movement in an operating direction to effect sheet-feeding cylinder rotation and in a return direction following such cylinder rotation; first stop means for limiting movement of said cylinder-operating member in said operating direction, said first stop means comprising a device for determining selectively two different lengths of movement of said cylinder-operating member in said operating direction; second stop means for limiting movement of said cylinder-operating member in said return direction; other means for rotating the cylinder to effect line-spacing movements thereof; means effective independently of preceding line-spacing accomplished by said other means for providing driving connection between said cylinder-operating member and said cylinder during the entire movement of said member from its limit position determined by said second stop means to its limit position determined by said first stop means, said drive connection means being ineffective during movement of said member from its limit position determined by said first stop means to its limit position determined by said second stop means; and means urging said cylinder-operating member in the return direction and yieldably holding it in the limit position determined by said second stop means.

4. In a typewriting or the like machine, the combination of a rotatable sheet-feeding cylinder; a gear connected to the cylinder; a rack adapted to mesh with the gear; a frame mounting said rack for reciprocatory movements; first stop means for determining the limit of movement of said rack in one direction on said frame; second stop means for determining the limit of movement of said rack in the opposite direction on said frame; means mounting the frame to move relatively to the gear to two positions for placing the rack respectively in mesh and out of mesh with said gear; releasable means effective when the rack is in the limit position determined by said second stop means and during movement of the rack to the limit position determined by said first stop means for holding said frame in position wherein it places the rack and gear in mesh; and means for releasing said holding means when the rack reaches the limit position determined by said first stop means for permitting the frame to move to its position wherein the rack and gear are placed out of mesh.

5. In a typewriting or the like machine, the combination of a rotatable sheet-feeding cylinder; a gear connected to the cylinder; a rack adapted to mesh with the gear; a frame mounting said rack for reciprocatory movements; first stop means for determining the limit of movement of said rack in one direction on said frame; second stop means for determining the limit of movement of said rack in the opposite direction on said frame; means mounting the frame to move relatively to the gear to two positions for placing the rack respectively in mesh and out

of mesh with said gear; releasable means effective when the rack is in the limit position determined by said second stop means and during movement of the rack to the limit position determined by said first stop means for holding said frame in position wherein it places the rack and gear in mesh; means for releasing said holding means when the rack reaches the limit position determined by said first stop means for permitting the frame to move to its position wherein the rack and gear are placed out of mesh, whereby said rack may return to its limit position determined by said second stop means without rotating the gear and cylinder; and means for restoring said holding means to holding position when said rack reaches said last-named position.

6. In a typewriting or the like machine, the combination of a rotatable sheet-feeding cylinder; a gear connected to the cylinder; a rack adapted to mesh with the gear; a frame mounting said rack for reciprocatory movements; first stop means for determining the limit of movement of said rack in one direction on said frame; second stop means for determining the limit of movement of said rack in the opposite direction on said frame; means mounting the frame to move relatively to the gear to two positions for placing the rack respectively in mesh and out of mesh with said gear; a first releasable means effective when the rack is in the limit position determined by said second stop means and during movement of the rack to the limit position determined by said first stop means for holding said frame in position wherein it places the rack and gear in mesh; means for releasing said holding means when the rack reaches the limit position determined by said first stop means for permitting the frame to move to its position wherein the rack and gear are placed out of mesh, whereby said rack may return to its limit position determined by said second stop means without rotating the gear and cylinder; a second releasable holding means for positively maintaining said frame in its last-named position to prevent meshing of said gear and rack during said rack return movement; and means responsive to rack return movement for rendering said second holding means ineffective and for restoring said first holding means to holding position when said rack completes its return movement.

7. In a typewriting or the like machine, the combination of a rotatable sheet-feeding cylinder; a gear connected to the cylinder; a rack adapted to mesh with the gear; a frame mounting said rack for reciprocatory movements; first stop means for determining the limit of movement of said rack in one direction on said frame; second stop means for determining the limit of movement of said rack in the opposite direction on said frame; means mounting the frame to move relatively to the gear to two positions for placing the rack respectively in mesh and out of mesh with said gear; a first releasable means effective when the rack is in the limit position determined by said second stop means and during movement of the rack to the limit position determined by said first stop means for holding said frame in position wherein it places the rack and gear in mesh; means for releasing said holding means when the rack reaches the limit position determined by said first stop means for permitting the frame to move to its position wherein the rack and gear are placed out of

mesh, whereby said rack may return to its limit position determined by said second stop means without rotating the gear and cylinder; a second releasable holding means for positively maintaining said frame in its last-named position to prevent meshing of said gear and rack during said rack return movement; means responsive to rack return movement for rendering said second holding means ineffective and for restoring said first holding means to holding position when said rack completes its return movement; and spring-powered means for urging said rack toward the position determined by said second stop means.

8. In a typewriting or the like machine, the combination of a rotatable sheet-feeding cylinder; a gear connected to the cylinder; a rack adapted to mesh with the gear; a frame mounting said rack for reciprocatory movements; first stop means for determining the limit of movement of said rack in one direction on said frame; second stop means for determining the limit of movement of said rack in the opposite direction on said frame; means pivotally mounting the frame to swing in a plane transverse to the axis of said gear to two positions selectively for placing the rack respectively in mesh and out of mesh with said gear; releasable means effective when the rack is in the limit position determined by said second stop means and during movement of the rack to the limit position determined by said first stop means for holding said frame in position wherein it places the rack and gear in mesh; and means for releasing said holding means when the rack reaches the limit position determined by said first stop means for permitting the frame to swing to its position wherein the rack and gear are placed out of mesh.

9. In a typewriting or the like machine, the combination of a rotatable sheet-feeding cylinder; a gear connected to the cylinder; a rack adapted to mesh with the gear; a frame mounting said rack for reciprocatory movements; first stop means for determining the limit of movement of said rack in one direction on said frame; second stop means for determining the limit of movement of said rack in the opposite direction on said frame; means mounting the frame to move relatively to the gear to two positions for placing the rack respectively in mesh and out of mesh with said gear; releasable means effective when the rack is in the limit position determined by said second stop means and during movement of the rack to the limit position determined by said first stop means for holding said frame in position wherein it places the rack and gear in mesh; and means for releasing said holding means when the rack reaches the limit position determined by said first stop means for permitting the frame to move to its position wherein the rack and gear are placed out of mesh; and a safety locking dog movable into locking engagement with said gear in response to the rack's reaching the limit position determined by said first stop means.

10. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin

on said frame; a holding member mounted to move on said carriage and having a part engageable with said pin when said rack is in the limit position determined by said second stop means and during movement of said rack from said limit position to its other limit position for maintaining said frame placed to hold the rack in mesh with the gear; and means responsive to movement of said rack to said other limit position for moving said holding member to disengage its said part from said pin to permit said frame to swing about its pivot to disengage said rack from said gear.

11. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin on said frame; a holding member mounted to move on said carriage and having a part engageable with said pin when said rack is in the limit position determined by said second stop means and during movement of said rack from said limit position to its other limit position for maintaining said frame placed to hold the rack in mesh with the gear; and means responsive to movement of said rack to said other limit position for moving said holding member to disengage its said part from said pin to permit said frame to swing about its pivot to disengage said rack from said gear, said holding member also having a part engageable by said pin for limiting that swinging movement of said frame and rack which disengages the rack from the gear.

12. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin on said frame; a holding member pivoted on said carriage and having a slot adapted to receive said pin when said rack is in the limit position determined by said second stop means and during movement of said rack from said limit position to its other limit position for maintaining said frame placed to hold the rack in mesh with the gear, said holding member also having an enlarged clearance opening communicating with said slot; and means on said rack engageable with said holding member when the rack is moved to said other limit position for rocking said holding member to free said pin from said slot and provide for movement of said pin within said clearance opening to permit said frame to swing and disengage said rack from said gear.

13. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for de-

termining the limit of cylinder operating strokes of said rack; second stop means for determining the limit of return strokes of said rack; a pin on said frame; a holding member pivoted on said carriage and having a slot adapted to receive said pin when said rack is in the limit position determined by said second stop means and during movement of said rack from said limit position to its other limit position for maintaining said frame placed to hold the rack in mesh with the gear, said holding member also having an enlarged clearance opening communicating with said slot; means on said rack engageable with said holding member when the rack is moved to said other limit position for rocking said holding member to free said pin from said slot and provide for movement of said pin within said clearance opening to permit said frame to swing and disengage said rack from said gear; a lifting finger movably mounted on said carriage; and spring means for urging said lifting finger to swing said frame and thereby disengage said rack from said gear when said pin has been freed from said slot.

14. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin on said frame; a holding member pivoted on said carriage and having a slot adapted to receive said pin when said rack is in the limit position determined by said second stop means and during movement of said rack from said limit position to its other limit position for maintaining said frame placed to hold the rack in mesh with the gear, said holding member also having an enlarged clearance opening communicating with said slot; means on said rack engageable with said holding member when the rack is moved to said other limit position for rocking said holding member to free said pin from said slot and provide for movement of said pin within said clearance opening to permit said frame to swing and disengage said rack from said gear; a lifting finger movably mounted on said carriage; and spring means connected between said holding member and said lifting finger and being adapted to be tensioned by movement of said holding member for urging said lifting finger to swing said frame and thereby disengage said rack from said gear when said pin has been freed from said slot.

15. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin on said frame; and a latch movably mounted on said carriage and normally disengaged from said pin but being engageable therewith when said rack is in the limit position determined by said first stop means for holding said rack out of en-

gagement with said gear during subsequent movement of said rack to its other limit position.

16. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin on said frame; a latch movably mounted on said carriage and normally disengaged from said pin but being engageable therewith when said rack is in the limit position determined by said first stop means for holding said rack out of engagement with said gear during subsequent movement of said rack to its other limit position; and means on said rack for moving said latch out of engagement with said pin when the rack reaches its said other limit position.

17. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a pin on said frame; a latch movably mounted on said carriage and normally disengaged from said pin but being engageable therewith when said rack is in the limit position determined by said first stop means for holding said rack out of engagement with said gear during subsequent movement of said rack to its other limit position; means on said rack for moving said latch out of engagement with said pin when the rack reaches its said other limit position; and spring means effective upon disengagement of said latch from said pin for urging said frame to swing said rack into engagement with said gear.

18. In a typewriting or the like machine, the combination of a carriage; a cylinder rotatable thereon for sheet feeding; a gear connected to the cylinder; a rack frame pivotally mounted on said carriage; a rack mounted to slide in said frame to perform cylinder operating and return strokes and to rock with said frame into and out of mesh with said gear; first stop means for determining the limit of cylinder operating strokes of said rack; second stop means for determining the limit of return strokes of said rack; a first pin on said frame; a holding member pivoted on said carriage and having a slot adapted to receive said pin when said rack is in the limit position determined by said second stop means and during movement of said rack from said limit position to its other limit position for maintaining the frame placed to hold the rack in mesh with the gear, said holding member also having an enlarged clearance opening communicating with said slot; means on said rack engageable with said holding member when the rack is moved to said other limit position for rocking said holding member to free said pin from said slot and provide for movement of the pin in said clearance opening; a lifting finger pivoted on said carriage and being adapted to move said pin within said clearance opening

and thereby move said frame and move said rack out of mesh with said gear; a second pin on said frame; a latch pivoted on said carriage and being engageable with said second pin when said rack is in the limit position determined by said first stop means for holding said rack out of mesh with the gear during subsequent movement of said rack to its limit position determined by said second stop means; means on said rack for swinging said latch out of engagement with said second pin when the rack reaches its last-named limit position, said lifting finger pivot being disposed between the holding member pivot and the latch pivot; and springs interposed between said lifting finger and said holding member and latch respectively.

19. In a typewriting or the like machine, the combination of a rotatable sheet-feeding cylinder; means for rotating the cylinder including a manually operable handle mounted to perform sheet-feeding strokes in one direction and idling return strokes in the opposite direction; means for determining the limit of said strokes in one of said directions; and a device for determining selectively a plurality of different limits of the strokes in the other of said directions, said device being adjustably mounted on said handle and being thereby conveniently adjustable by the operator's hand when it is grasping said handle.

20. In a typewriting or the like machine, the combination of a rotatable sheet-feeding cylinder; means for rotating the cylinder including a manually operable handle mounted to perform sheet-feeding strokes in one direction and idling return strokes in the opposite direction; means for determining the limit of said strokes in one of said directions; and a device for determining selectively two different limits of the strokes in the other of said directions for selecting one of two different lengths of sheet movements to be effected by a sheet-feeding stroke of said handle, said device comprising a relatively fixed first stop with respect to which said handle is movable bodily, a second stop carried by and movable with said handle and being engageable with said relatively fixed stop, and a third stop carried by and movable bodily with said handle and being movable with respect to the handle to one position for being engageable with said first stop and to another position such that movement of said handle will not bring said third stop into engagement with said first stop, said third stop when in its said first position being disposed between said first stop and said second stop and when in its said other position being disposed other than between said first stop and said second stop, said second stop being engageable with said first stop only when said third stop is in its said other position.

21. In a typewriting or the like machine, the combination of a rotatable sheet-feeding cylinder; means for rotating the cylinder including a manually operable handle mounted to perform sheet-feeding strokes in one direction and idling return strokes in the opposite direction; means for determining the limit of said strokes in one of said directions; and a device for determining selectively two different limits of the strokes in the other of said directions for selecting one of two different lengths of sheet movements to be effected by a sheet-feeding stroke of said handle, said device comprising a relatively fixed first stop with respect to which said handle is movable bodily, second and third stops carried by and

being bodily movable with said handle, said third stop being adapted to be positioned selectively in the line of movement of said second stop toward said first stop and out of said line of movement, and means for moving said third stop selectively into or out of said line of movement.

22. In a typewriting or the like machine, the combination of a rotatable sheet-feeding cylinder; a gear connected to the cylinder; a rack adapted to mesh with the gear; means for mounting the rack for reciprocation; a first stop on said rack-mounting means; a second stop fixed to said rack and being adapted to engage said first stop upon movement of said rack; and a third stop mounted on said rack between said first and second stops and being movable on said rack selectively to a position in which it is engageable with said first stop upon movement of the rack and to another position in which it is not so engageable with said first stop.

23. In a typewriting or the like machine, a movable sheet-feeding element; line-spacing means for driving said element in step-by-step increments; and means including a gear drivingly connected to said element and a reciprocable operating rack adapted to mesh with said gear and being movable in one continuous operating

stroke following one or more step-by-step movements effected by the line-spacing means to present a predetermined point of the sheet at the typing line irrespective of the number of step-by-step movements which were effected by said line-spacing means prior to said stroke of said rack, and means for holding said rack in mesh with said gear during operating strokes of the rack and for holding said rack out of mesh with the gear during return strokes of the rack.

24. In a typewriting or the like machine, a movable sheet-feeding element; line-spacing means for driving said element in step-by-step increments; a gear in constant driving connection with said sheet-feeding element; an operating rack; means mounting said rack for reciprocation between limits at the ends of operating strokes and return strokes respectively; and means for effecting meshing of the rack with the gear when the rack is at rest at the limit at the end of its return stroke and from the time the rack leaves the limit at the end of a preceding return stroke until the rack reaches the limit of the operating stroke and for maintaining said rack and gear out of mesh during the following return stroke.

GEORGE F. HANDLEY.
